US00D945453S

(12) **United States Design Patent** (10) **Patent No.:** **US D945,453 S**
(45) **Date of Patent:** **** Mar. 8, 2022**

(54) **DISPLAY SCREEN PORTION WITH ANIMATED GRAPHICAL USER INTERFACE**

(71) Applicant: **William Grecia**, Downingtown, PA (US)

(72) Inventor: **William Grecia**, Downingtown, PA (US)

(73) Assignee: **FINTECH INNOVATION ASSOCIATES LLC**, Downingtown, PA (US)

(**) Term: **15 Years**

(21) Appl. No.: **29/808,027**

(22) Filed: **Sep. 16, 2021**

(51) LOC (13) Cl. **14-04**

(52) U.S. Cl.

USPC **D14/485**

(58) **Field of Classification Search**

USPC **D14/485-495**
